UNITED STATES PATENT OFFICE.

JAMES OPPENHEIM, OF NEW YORK, N. Y., ASSIGNOR TO WYCKOFF, SEAMANS & BENEDICT, OF ILION, NEW YORK, A CORPORATION OF NEW YORK.

TYPE-WRITING MACHINE.

SPECIFICATION forming part of Letters Patent No. 767,429, dated August 16, 1904.

Application filed April 15, 1903. Serial No. 152,735. (No model.)

To all whom it may concern:

Be it known that I, JAMES OPPENHEIM, a citizen of the United States, and a resident of the borough of Manhattan, city of New York, in the county of New York and State of New York, have invented certain new and useful Improvements in Type-Writing Machines, of which the following is a specification.

My invention relates to tabulating mechanism for type-writing machines.

It is usual in tabulating mechanism for type-writing machines to employ a series of column-stops either on a fixed portion of the machine or on the carriage and with which one or more arresting-stops coöperate. In such machines when the stops are brought into coöperative relation and the carriage is free to travel the arresting-stop necessarily engages the first of a series of column-stops (supposing the carriage to be at the extreme right) and thereafter engages successively the remaining column-stops. In certain classes of type-writing work in which it is desired to employ the number of column-field stops for defining a plurality of columnar fields upon the sheet to be printed it often happens that in certain of the lines of writing no entry is required in the first or, perhaps, in several of the first series of columnar fields, the entry or entries being made only in the last one or more of the predetermined columnar fields. Usually tabulating mechanisms heretofore employed have been subject to the objection that under all conditions the carriage when released from its escapement was necessarily arrested at the first and at each succeeding column-stop until it finally reached the stop at which the desired entry was to be made.

One of the objects of my present invention is to overcome these difficulties and to provide means whereby a carriage may be arrested at any of a number of predetermined columnar positions without being first checked or arrested by other column-stops.

It has likewise been customary heretofore to provide type-writing machines with so-called ordinary "tabulating" or "column-stop" mechanism wherein the carriage is ar-

rested at the proper column and at a point where the printing-point is at a position corresponding to, say, the units position in the column of figures to be written within the columnar field. Again, the machines have heretofore been provided with so-called "denominational-stop" mechanism wherein the carriage is arrested so as to bring the printing-point to the proper denominational position in the column of figures within the columnar field at which the carriage is arrested.

A further object of my invention is to provide both characters of tabulating mechanisms above referred to and to provide simple and efficient means whereby either the column-stop mechanism or the denominational-stop mechanism, or both, may be brought into operation.

To the above and other ends, which will hereinafter appear, my invention consists in the features of construction, arrangements of parts, and combinations of devices to be hereinafter described, and particularly pointed out in the appended claims.

In the accompanying drawings, wherein like reference characters indicate corresponding parts in the various views, Figure 1 is a vertical front-to-rear central sectional view of one form of type-writing machine embodying my invention. Fig. 2 is a plan view of the same with parts broken away. Fig. 3 is a fragmentary view which corresponds to Fig. 1, except that in Fig. 1 a normal disposition of the parts is shown, whereas Fig. 3 represents one of the tabulating-keys (shown in full lines) depressed and another (shown in dotted lines) pushed longitudinally toward the rear of the machine. Fig. 4 is a detail perspective view of the tabulating mechanism. Fig. 5 is a rear elevation of the various sets of stops carried by the carriage with some of the parts broken away. Fig. 6 is a transverse sectional view of the same, the section being taken on the line $\alpha\alpha$ of Fig. 5. Fig. 7 is a detail perspective view of one of the stepped denominational stops. Fig. 8 is a detail front elevation of the actuating-bar through which the tabulating-key levers extend, the levers

being shown in section. Fig. 9 is a detail front elevation of the arresting-bar for the tabulating-key levers.

In the various views parts have been omitted and parts broken away in order to more clearly illustrate other features of the construction.

I have shown my invention applied to a No. 6 Remington type-writing machine, though it should be understood that the invention or any of the various features thereof may be applied to other characters of type-writing machines.

The frame 1 of the machine is surmounted by a top plate 2, that has upwardly-extending lugs 3, to which a traverse-rod 4 is fixed. The carriage 5 carries antifriction-rollers 6, which bear upon the traverse-rod and support and guide the carriage in its movement from side to side of the machine. The carriage is also guided by a traverse-rod 7, with which an arm 8, that is connected to the carriage, cooperates. A platen 9 is supported by the carriage or its platen-frame and is adapted to revolve therein. The forward portion of the carriage carries a roller 10, that is supported upon a shift rail or rod 11, that may be actuated by the usual or any suitable means. A carriage feed-rack 12 is secured to the forward ends of curved arms 12^a, that bridge the traverse-rod and are pivoted to the carriage at 13. Extending downwardly and rearwardly from the arms 12^a and beyond the pivots thereof are arms 14, which carry a bar 15, that extends throughout or substantially throughout the length of the feed-rack and carriage. The feed-rack 12 meshes with the feed-pinion 16, that is fixed upon the forward end of a shaft adapted to rotate in a bearing 17, which is secured to the top plate of the machine. The rear end of this shaft is operatively connected to an escapement-wheel 18, with which the feed-dogs 19 and 20 coöperate. The feed-dogs are carried in the usual manner upon a dog-rocker 21, the rock-shaft 22 of which is mounted in suitable bearings in the frame of the machine and has a forwardly-extending crank-arm 23, to which a transverse bar 24 is secured. Connected to each end of the transverse bar is a depending link 25, that is connected at its lower end to a universal bar 26, which extends beneath the series of key-levers 27, fulcrumed at 28 and provided with the usual finger-keys 29 at their forward ends.

A restoring-spring 30 is connected at one end to the rock-shaft and at its other end 31 to a fixed bracket-plate that supports the bearings for the rock-shaft 22 of the dog-rocker. Each of the key-levers is connected to a link 32, which in turn is pivoted at its upper end 33 to a type-bar 34. Extending beneath the series of key-levers and out of the paths of movements thereof are a series of tabulator-key levers 35, each of which is slotted at 36 and has a fixed pivot-rod 37, that extends

through a slotted portion thereof and is secured at its ends at the sides of the machine. These tabulating-key levers are each connected to one end of a contractile spring 38, the opposite end of each spring being secured at 39 to an arresting-bar 40, which is fixed at its ends to the sides of the framing of the machine and has secured thereto a series of restoring-springs 41, each of which bears on a tabulating-key lever forward of its pivot in order to restore its key-lever to the normal position considered with relation to the pivotal movement thereof. From the foregoing description it will be seen that each of the tabulating-key levers is capable of moving in two directions—that is to say, it is capable of a pivotal movement around the fixed pivot 37 and is likewise capable of a sliding movement fore and aft of the machine by reason of the slot 36 therein. The contractile spring 38 of each key-lever tends to restore it to its normal position considered with relation to its longitudinal movement or the movement thereof fore and aft of the machine. The various key-levers project through openings 42 in a so-called "controlling-bar" 43, and each of these levers is provided with a finger-key 44 at the outer end thereof, which is of sufficient size to prevent the key or head from passing through the associated opening 42 in the bar, so that when a key is moved toward the rear of the machine it will take up the bar 43 near the end of its movement and cause the bar to move with it.

Each finger-key has two faces, one at an angle to the other. Thus each key-lever has an inclined face 45 and a vertical face 46, the inclined faces bearing one set of indices, whereas the vertical faces bear another set of indices, and the bar 43 has an inclined upper edge 43^a, that bears a third set of indices, one at each tabulating-key, all for purposes which will hereinafter appear.

Various tabulating-key levers are received within guiding-slots 47 in the fixed stop-bar 40. These slots in the stop-bar 40 are at various depths, as indicated in Fig. 9, so that different extents of depression are afforded different key-levers in their pivotal movements. Thus, for instance, nine tabulating-key levers are shown, and the key-lever at the left hand in Fig. 9 has the greatest extent of depression by reason of the fact that the deepest slot 47 is provided for this key-lever. The depth of the slots gradually decreases from left to right until the two right-hand tabulating-keys 35^x are reached, where the bottom walls of the slots 47 are coextensive with the bottoms of the key-levers when the latter are in their normal positions, so that these two levers, which bear the numerals "8" and "9" on the inclined faces 45, normally rest at the bottoms of their respective slots of the stop-bar 40, and no pivotal movement therefore can be given to these key-levers, merely a reciprocating move-

ment fore and aft of the machine. The so-called "controlling-bar" 43 has depressions 48, which correspond to the slots 47 in the stop-bar, and certain of the tabulating-key levers—
5 as 35^a, 35^b, and 35^c, for instance—are made of greater width, considered vertically, than the others. The object of this arrangement is to take up the controlling-bar 43 at a given period during the depression of any of the tabulating-
10 keys, notwithstanding the fact that the various tabulating-keys have different extents of depression in order that the carriage-releasing mechanism, which is controlled by the controlling-bar 43, may be released at a pre-
15 determined time relatively to the completion of the depression of any of the various tabulating-keys, as will hereinafter more clearly appear. The controlling-bar 43 is secured near its ends to bars or levers 49, that correspond substan-
20 tially to the tabulating-key levers—that is to say, each of the bars 49 has a slot 50, through which the pivot-rod 37 projects and has a contractile spring 51, that tends to move it toward the front of the machine, whereas a leaf-
25 spring 52 restores the bar or lever to its normal position considered with relation to the pivotal movement thereof. Each of these bars or levers 49 is likewise received in a guiding-slot 53 in the stop-bar 40. The sole purpose, 30 however, of the slots 53 for these levers is to provide a guiding-slot for the levers in their reciprocating and pivotal movements. The rear end portions of these levers 49 are connected by a rod 49^a, so as to constitute, with 35 the bar 43, a rectangular frame that is movable in two directions, one a pivotal movement around the pivot-rod 37 and the other a reciprocating or sliding movement fore and aft of the machine. The rear ends of the levers 49 are bent upwardly at 54, and bearing pins or 40 screws 55 rest on the upper edges of the upwardly-bent portions. The bearing pins or screws 55 are carried by and extend laterally from bell-cranks 56, which are secured 45 to a rock-shaft 57, pivoted in the base of the frame 1 of the machine. The upwardly-extending arms of these bell-crank levers are united by a bar 58, that extends in front of and adjacent to a depending arm 59, which 50 projects from a rock-shaft 60, pivoted in a fixed bracket 61, and which carries a crank-arm 62, that extends upwardly and then forwardly, as indicated at 63, and has the free end thereof extending normally adjacent to 55 the bar 15, that is connected to the carriage feed-rack 12.

From the foregoing description it will be understood that a depression of any of the depressible tabulating-keys will cause the controlling-bar 43 to be depressed during the last portion of the stroke of said key, thereby elevating the rear end of the frame, of which the bar 43 forms a part, thus swinging the bell-crank levers 56 on their piv-
60 al center. The effect of this movement is

to move the depending arm 59 rearwardly through the bar 58, thus swinging the upper arm 63 forwardly against the bar 15 to effect an elevation of the feed-rack, thus releasing the carriage from its escapement mechanism. 70 When the tabulating-key is released, the parts will be restored to their normal positions by a contractile spring 64, which is connected at one end to the depending arm 59 and at the opposite end to a fixed portion of the 75 machine, as indicated at 65, and this spring in effecting a forward movement of the arm 59 causes it to move the bar 58 in the same direction, thus swinging the carriage-releasing frame on its pivot 37, so as to elevate the 80 bar 43 of said frame to the normal position, whereas the spring 41 of the depressed tabulating-key is effective to restore it to the normal position.

The depending arm 59 likewise carries at 85 the lower end thereof a transversely-extending bar 66, with which the hook-like ends 67 of the levers or bars 49 are adapted to co-operate. Thus the pushing movement of any 90 of the tabulating-keys toward the rear of the machine will bring it into contact with the controlling-bar 43 during the latter portion of the stroke of the key, thereby moving the frame, of which the bar 43 forms a part, in the same direction. This movement is effect- 95 ive to bring the hook-like portions or ends 67 of the bars 49 of the frame into contact with the transversely-extending bar 66 and to move it rearwardly, thereby swinging the arm 63 forwardly to effect a release of the 100 carriage from its escapement mechanism in the manner hereinbefore described. It will be understood that the arm 63 is adapted to effect a release of the carriage irrespective of the 105 position to which the carriage may have traveled, inasmuch as the bar 15, with which the arm 63 co-operates, extends substantially throughout the length of the carriage.

I have described the means whereby either a pivotal movement or a longitudinal move- 110 ment of any of the tabulating-keys is effective to release the carriage at or near the end of the stroke of said key, and I will now de- 115 scribe how the same movements are effective to interpose either of two arresting-stops in the path of a co-operating stop or stops on the carriage. Extending transversely across and above the various tabulating-key levers is a bar 68, that constitutes a part of a frame, the upwardly-extending side members 69 of 120 which are received in openings in brackets 70, secured to the frame of the machine, so that the frame of which the members 68 and 69 form parts is guided in its vertical movements. A coiled spring 71 surrounds each of the up- 125 right members 69 and bears at one end against a collar 72 on said member and at its opposite end against the associated bracket 70. The upper end of each member 69 is provided with a collar 73, which in the normal position 130

of the frame rests upon the upper face of its associated bracket 70. A cross-bar 74 is connected to the upper ends of the upright members 69 and carries an upwardly-extending 5 plunger-arresting stop 75, which is received in and projects through a guiding-opening in a cross-bar 76^a of a bracket 76, secured to the top plate of the machine. On the depression of any of the depressible tabulating-key levers the rear end thereof is brought into contact with the cross-bar 68, thereby elevating the frame of which it constitutes a part, thus raising the stop 75 and interposing it in the path of one of the coöperating column stops 10 or shoulders 77, carried by the carriage. These stops or shoulders 77 are in the nature of graduated or step-shaped stops that are formed upon a bar 78, the upper edge of which is secured to a stop-bar 79 or which is made integral with the bar 79. These shoulders or stops 77 are preferably arranged at ten letter-space distances apart and correspond to the seventy letter-spaces on the scale of the machine divided into divisions of ten. It has heretofore been explained that each of the first seven tabulating-keys counting from the right and bearing the numerals "10" to "70" have different extents of dip, so that a different extent of movement will be given to the stop 75 15 at the depression of each of said keys, the greatest extent of dip being afforded the key bearing the numeral "10" and the least extent of dip being afforded the numeral "70." If, therefore, the operator depresses the key bearing the numeral "10," the stop 75 will be elevated to its greatest extent, thereby bringing it into the path of the highest of the step-shaped stops 77 on the carriage, and the carriage will be arrested at the tenth 20 letter-space distance on the scale, assuming that the carriage is at the extreme right when the tabulating-key is depressed. If, on the other hand, the seventh key or that marked with the numeral "70" is depressed, the least extent of vertical movement will be given to the stop 75, and it will be brought into the path of the lowest stop 77 on the carriage, thereby permitting a free run of the carriage until the last or lowest of the series of step-shaped stops 77 is reached, and the carriage will be arrested at the point "70" on the scale and so that the depression of any of the intermediate keys will arrest the carriage at the proper point indicated by the numeral on 25 the end of the key depressed.

The stop-bar 79, hereinbefore referred to, is divided into seven series of step-shaped stops 80, that are located at letter-space distances apart, and the stops of each series, there being nine in each series, are progressively arranged at greater distances fore and aft of the machine. Coöperating with the stops 80 is a plunger-arresting stop 81, carried by a slide 82, that is adapted to move in a bearing 60 65 83, carried by the bracket 76, which is se-

cured to the top plate of the machine. One side of the bearing 83 is slotted at 84 to receive a pin 85, which projects from the slide 82 through the slot and is received within a slotted opening 86 in the end of an arm 87, 70 guided in the slotted portion 88 of the bracket 76, the arm 87 projecting from a rock-shaft 89, pivoted in the fixed brackets 61. Depending from the rock-shaft 89 is an arm 90, that carries a transversely-extending bar 91 at its 75 lower end, which bar extends beneath the various tabulating-key levers. A coiled spring 92 surrounds the rock-shaft 89 and is secured at one end 93 to the depending arm 90, whereas the other end of said spring is secured to 80 one of the brackets 61, so that the tension of said spring is exerted to restore the rock-shaft and the parts connected thereto to the normal positions. (Illustrated in Figs. 1 and 5.) Each of the nine tabulating-keys carries a depending abutment 94, that is adapted to contact with the transverse bar or rod 91 when the key-lever which carries it is moved toward the rear of the machine, thus moving said bar toward the rear to effect a forward movement of the arm 87 and the stop 81, which is connected thereto. The depending abutments 94 on the various tabulating-key levers are arranged at progressively greater distances from the rear ends of the lever and toward 95 the front of the machine, beginning with the left-hand tabulating-key and ending with the right-hand tabulating-key. While the various tabulating-keys receive a given extent of reciprocating movement fore and aft of the machine, the bar 91 and the parts controlled thereby will receive different extents of movement by reason of the different disposition of the various abutments 94 on the different tabulating-keys. Thus if the left-hand tabulating-key bearing the numeral "1" is pushed toward the rear of the machine it will cause the abutment 94 thereon to force the bar 91 toward the rear, giving the longest throw thereto, thereby bringing the movable 100 stop 81 into the path of the first stop 80 of one series or that stop of the series which is nearest the front of the machine, thus permitting the carriage to move one letter-space distance. If, on the other hand, the right-hand 105 key bearing the numeral "9" is pushed toward the rear of the machine, then the bar 81 will receive its shortest extent of rearward movement and will interpose the stop 81 in the path of the rearmost stop 80 of one series, thereby 110 permitting the carriage to travel nine letter-space distances. It will therefore be seen that the carriage may be arrested at any one of nine letter-space distances, determined by which key of the nine is pushed toward the 115 rear of the machine. It has heretofore been explained that the pushing in of any of the tabulating-keys in the manner described will bring the head thereof into contact with the bar 43, thereby moving the frame, of which 120 125 130

the bar 43 constitutes a part, toward the rear of the machine. The effect of this movement is to move the bar 66 rearwardly, thereby releasing the carriage from its escapement mechanism, as heretofore explained. This latter movement, however, is not effected until the latter part of the reciprocating or rearward movement of any key and does not take place until the stop 81 has been or is just about to be interposed in the path of a coöperating stop 80 on the carriage.

The stop-bar 79 is provided at its ends with depending ears or lugs 95, which are apertured for the reception of headed screw-pivots 96, the stems of which extend through openings therein and into threaded openings in upwardly-projecting lugs 97, that extend from the carriage. The stems of these screw-pivots likewise extend through openings in lugs or ears 98, which project laterally from the ends of a rack-bar 99, the teeth of which are situated a letter-space distance apart and correspond to the carriage-scale. The lugs 98 carry laterally-extending pins 100, which project upon opposite sides of the stop-bar 79, as indicated in Figs. 5 and 6, so that the stop-bar 79, with its stop-bar 78 and rack 99, are locked to turn together on the pivots 96. The lugs 98 likewise carry spring-catches 101, each of which has an engaging projection 102, that is adapted to engage under the flange 103 of the transversely-extending rear carriage-rail, as illustrated in Fig. 6, when the parts are turned on their pivots 96 to the position indicated in this figure for a purpose which will herein-after appear.

From an examination of Fig. 7 it will be seen that a stop-carrier 104 has graduations or step-shaped stops 105 thereon and that from the base 106 of the carrier project teeth or fingers 107, which are three in number. Each of these teeth or fingers has a hook-like portion 108, and secured to one edge of the base 106 are spring-catches 109, each of which terminates in a curved or projecting portion 110. The construction of each of these stop-carriers, or "stops," as they may be termed, is such that the teeth 107 may be seated within spaces between the teeth 111 on the rack-bar 99, and the hook-like portions of the teeth 107 will engage the body of the rack-bar, as illustrated in Figs. 5 and 6. At this time the bent ends of the spring-catches 109 will engage in a depressed portion 112 in the body 55 of the rack-bar, and thus maintain the stop or stop-carrier in locking engagement with its rack. This construction is such that the carrier may be readily connected to or disconnected from the rack-bar and adjusted at any desirable point along the rack. It will be understood that any suitable number of these stop-carriers may be employed on the rack 99 and that when in position the stops 105 will extend in the same general direction as the stops 65 77 on the bar 78, as illustrated in Fig. 5, the

planes of the carriers or body portions of said stops being parallel, as indicated in Fig. 6. When the stops or stop-carriers 104 are in position, there will be three groups or stops carried by the carriage—viz., the stops 77, 70 the stops 80, and the stops 105—all of which are connected together and are secured to virtually constitute a frame that is pivoted to the carriage and is adapted to be swung and maintained either in the position represented 75 in Fig. 1 or in the position shown in Fig. 6. When the parts are in the position shown in Fig. 1, the stops 105 are moved to a position where they are inoperative for any purpose, and at this time the stops 77 and 80 are adapted 80 to coöperate with the arresting-stop 75 and 81, respectively. When, however, the pivoted frame is shifted to the position shown in Fig. 6, the stops 77 and 80 become inoperative, being moved to a position where they can no 85 longer coöperate with the stops 75 and 81. The stops 105, however, are at this time moved to a position where the stop 81 when moved forward will coöperate therewith.

In order to insure the proper movement of 90 the tabulating-key levers, whether it be a reciprocating or a pivotal movement, the rear end of each lever is received within a guide, the upright groove or guide 113, which guides the rear end of the lever in its vertical movement, and the horizontal groove or guide 114 guiding the rear end of the lever in its horizontal or reciprocating movement. From an examination of Fig. 1, which illustrates the parts in their normal positions, it will be seen that 95 the rear end of each tabulating-key lever is normally disposed at the point of intersection of the two grooves 113 and 114 and at this time the key may be either depressed or moved toward the rear of the machine. If a key is depressed, 105 the rear end of its lever will be immediately moved out of register with or away from the groove or guide 114, and the rear wall of the groove or guide 113 will prevent the key-lever from being pushed rearwardly until it again 110 assumes the normal position. If, on the other hand, a key-lever is moved rearwardly from the normal position, the rear end is immediately carried beyond the groove 113, and the top wall of the groove 114 will prevent an upward movement of the rear end of the key-lever and will consequently prevent a depression of its key. It will therefore be seen that means are provided to guide each key-lever and insure a proper movement thereof, 115 whether it be a pivotal movement or a longitudinal reciprocating movement, once a key-lever is started in either direction.

Each tabulating-key lever is limited in its rearward movement by a shoulder 115 thereon 120 being brought into contact with a rear wall of its groove 113, which prevents further rearward movement of the lever, thus insuring uniform extent of rearward movement of all the tabulating-key levers, as heretofore stated. 130

Assuming that the parts are set, as represented in Fig. 1, so that the stops 77 and 80 are in the operative position and that the carriage is at the extreme right and the operator 5 wants to stop the carriage at the point "40" on the scale with the tabulating mechanism, it is merely necessary to depress the tabulating-key bearing the numeral "40," which is effective to move the stop into the path of the 10 fourth stop 77 and to release the carriage, when it will travel to the left until the fourth stop 77 arrives at stop 75. The first, second, and third stops 77 at this time being at a 15 higher elevation than that to which the stop 75 has been moved will be out of its reach and will not be affected thereby, and the carriage will be arrested at "40" on the scale. Should the operator desire to arrest the carriage at "45," for instance, with the tabulating 20 mechanism, it is merely necessary to depress the tabulating-key bearing the numeral "40," as previously described. After the carriage has traveled to and been arrested at "40" on the scale release the key and push 25 the "5" key rearwardly. The effect of this is to bring the stop 81 into the path of the fifth stop 80 of the fourth series of nine each and at the same time to release the carriage and permit it to move five letter-space 30 distances, or until the fifth stop 80 of the fourth series is brought into contact with the stop 81. The key-lever may then be released, and the parts will be restored to the normal positions by their several springs and the carriage 35 positioned at "45" on the scale. It will therefore be seen that two separate arresting-stops are adapted to be moved to different extents by the same set of tabulating-keys, a movement of the keys in one direction moving 40 one of the stops, whereas a movement of the keys in another direction actuates the other stop. Thus the stop 75 is projected to different extents into the path of the stop 77, which are situated ten letter-space distances apart, 45 and the carriage may at once and by a single actuation of the one of the tabulating-keys be arrested at any of the divisions controlled by these stops. On the other hand, the stop 81 is projected to different extents into the paths 50 of the stops 80 of any set thereof, each set being nine in number, so that the proper letter-space position within any division between the stops 77 may be attained. If the point at which the carriage is to be arrested is at "10" 55 or any multiple thereof up to "70," a single actuation or reciprocating movement of any of the tabulating-keys will effect the result, whereas if the carriage is to be arrested at a point other than "10" or any multiple thereof up to "70" then an actuation or reciprocation 60 of one of the tabulating-keys is first required and then a subsequent depression thereof in order to arrest the carriage at the proper position.

65 While I have described that the rack-bar

78 has its stops 77 located at ten letter-space distances apart, it should be understood that the stops may be situated at greater or less intervals apart. It should likewise be understood that while I have described the stop-bar 79 as provided with seven series of stops 80, nine stops being provided in each series, the stop-bar may be otherwise provided and a fewer or greater number of series of such stops may be employed. 75

It will be understood that the screw-pivots 96 permit of the withdrawal or dismounting of the frame, of which the stop-bars 78 and 79 and rack-bar 99 constitute parts, so that stop-bars of different characters may be employed or frames having stop-bars of different characters may be substituted one for another. 80

By pivoting the frame comprising the various stop-bars and rack 99 in the manner described I am enabled, as heretofore described, to turn the frame to the position shown in Fig. 6 and to lock it in such position by the check-springs 101, thus maintaining the stops 77 and 80 out of the operative position and 90 bringing the stops 105 to a position where they are adapted to coöperate with the plunger or arresting-stop 81. This arrangement is such that one or more carriers 104 having graduations are provided, which may be adjusted to the desired positions along the rack-bar 99, and a denominational tabulating mechanism is thereby provided. The adjustment of the stop-carriers 104 regulates the columnar positions, and at the same time the step-shaped 100 stops 105 afford an arresting of the carriage at different denominational positions, as determined by the extent of movement of the co-operating plunger-stop 81. From an examination of Fig. 4 it will be seen that a set 105 of indices are carried on the inclined face 43^a of the bar 43, as heretofore described. These indices correspond with different denominational positions—such as units, tens, hundreds, &c.—and commence at the third 110 key from the right and are situated adjacent to the tabulating-key levers with which they are associated. Thus the letter "u" designates the third key from the right, which corresponds to the units position, whereas the index "t" designates the next key to the left, which corresponds to the tens position, and the index "h" is adjacent to the next key to the left and indicates the hundreds position, and so on up to the seventh or millions key, 120 adjacent to which is the index "m," it being borne in mind that a rearward sliding movement of the tabulating-keys will effect a forward movement of the stop 81 to different extents. It will be understood that the greatest extent of this movement will be effected by a rearward movement of the first key from the left, which is the millions key, thereby carrying the stop 81 into the path of the first 125 stop 105, or that next to the rack. On the 130

other hand, a rearward movement of the seventh key from the left, which is last of the 5 depressible keys, projects the stop 81 into the path of the stop 105, which is farthest from the rack-bar, thereby arresting the carriage at the units position, (indicated by the index "u,") so that an efficient denominational tabulator which is actuated in the ordinary manner is produced by merely locking the frame 10 carrying the stop-bars 78 and 79 and rack 99 in the position shown in Fig. 6.

It will be seen that three separate sets of indices are provided for the tabulating-keys, one of which consists of the numerals "1" to 15 "9" on the inclined faces 45 of the keys and which designate the nine positions to which the carriage may be moved within a division of the stops 77. The other set of indices consists of the numerals "10," "20," and so on up 20 to "70," on the forward vertical faces of the first seven keys, counting from left to right, and which indicate the keys that control the arrest of the carriage for the seven divisions at ten letter-space distances apart and which 25 is effected by the plunger-stop 75 and the series of stops 77 when the key-levers are pushed toward the rear of the machine. The third set of indices consists of the marks "u," "t," "h," "1t," "10t," "ht," and "m," adjacent 30 to the first seven keys, counting from the left, and which indicate the denominational arrest of the carriage to any position from the units to millions by a single actuation of any of the tabulating-keys when the stops 105 are employed. 35

From the foregoing description it will be understood that the stops 77 constitute column-stops and that the stops 75, which coöperate therewith, constitute what may be termed a 40 "column" arresting-stop, that the stops 80 and 105 constitute denominational stops, which enable the carriage to be arrested at the proper letter-space or denominational position within the column, and that the stop 81 coöperates 45 with either the stops 80 or the stops 105 to arrest the carriage in such positions and may be termed a "denominational" arresting-stop, that the stops 75 and 81 are actuated independently of each other by the same keys, a movement 50 of a key-lever in one direction (a pivotal movement) actuating the stop 75, whereas a movement in another direction (a longitudinal movement toward the rear of the machine) effects an actuation of the stop 81, and that a 55 movement of the keys in either direction automatically effects a release of the carriage, that the stop 77, each set of nine stops 80, and the stops 105 on the carrier 104 may in each instance be regarded as graduated stops or a 60 set of graduated stops, that the guides 113 and 114 constitute, respectively, vertical and horizontal guides for the tabulating-key levers, and that when a lever is seated and starts to move in one guide it is prevented from moving 65 in any direction other than that which is

permitted by the guide in which the lever is seated.

While I have shown and described with considerable particularity one form of construction embodying my invention, it should 70 be understood that various changes may be made without departing from the spirit of my invention and that from certain aspects of my invention certain features may be employed without the others. 75

What I claim as new, and desire to secure by Letters Patent, is—

1. In a type-writing machine, the combination of a carriage, key-actuated denominational stop mechanism and key-actuated column-stop mechanism, either of which can be actuated separately by the same keys to arrest the carriage. 80

2. In a type-writing machine, the combination of a carriage, key-actuated denominational-stop mechanism, key-actuated column-stop mechanism, either of which can be actuated separately by the same key to arrest the carriage, and means for automatically releasing the carriage when either mechanism is actuated. 85

3. In a type-writing machine, the combination of a carriage, denominational-stop mechanism, and column-stop mechanism, either of which can be actuated separately at will, and 95 a single set of keys for operating either the denominational or the column stop mechanism to arrest the carriage. 90

4. In a type-writing machine, the combination of a carriage, denominational-stop mechanism, column-stop mechanism, either of which can be actuated separately at will, a single set of key-levers for operating either the denominational or column stop mechanism, and means controlled by said key-levers for automatically 100 releasing the carriage when they are operated to actuate either the column stop or denominational stop mechanism. 105

5. In a type-writing machine, the combination of a carriage, a set of denominational 110 stops, an independent stop coöperating therewith, a separate set of column-stops, an independently-actuated stop coöperating therewith and a single set of keys for actuating either of said independent stops, whereby 115 either the denominational or column stop mechanism may be employed at will to arrest the carriage. 120

6. In a type-writing machine, the combination of a carriage, a set of denominational stops carried by the carriage, a stop coöperating therewith, a set of independent column-stops carried by the carriage, a stop coöperating therewith, and single-key-actuated means for bringing either the denominational or the column stops into operation at will and for automatically releasing the carriage. 125

7. In a type-writing machine, the combination of a carriage, a set of denominational stops, an independently-operable stop coöperating 130

therewith, a set of independent column-stops, an independently-operable stop coöperating therewith, a single-key-actuated means for actuating either of said independently-operable stops, thereby bringing either the denominational or the column stops into operation, and means for automatically releasing the carriage when said key-actuated means are operated.

8. In a type-writing machine, the combination of a carriage, two stops which are adapted to effect the arrest of the carriage, and a key which when moved in one direction will effect a movement of one of said stops and when moved in another direction will effect a movement of the other stop.

9. In a type-writing machine, the combination of a carriage, two stops which are adapted to effect the arrest of the carriage, a key which when moved in one direction will effect a movement of one of said stops and when moved in another direction will effect a movement of the other stop, and carriage-releasing means controlled by an actuation of said key.

10. In a type-writing machine, the combination of a carriage, a denominational arresting-stop, denominational stops that coöperate therewith, a column arresting-stop, column-stops that coöperate therewith, and a key which when moved in one direction will effect a movement of the denominational arresting-stop and when moved in another direction will effect a movement of the column arresting-stop.

11. In a type-writing machine, the combination of a carriage, a denominational arresting-stop, denominational stops that coöperate therewith, a column arresting-stop, column-stops that coöperate therewith, a key which when moved in one direction will effect a movement of the denominational arresting-stop and when moved in another direction will effect a movement of the column arresting-stop, and means controlled by said key for automatically releasing the carriage.

12. In a type-writing machine, the combination of a carriage, a denominational arresting-stop, denominational stops that coöperate therewith, a column arresting-stop, column-stops that coöperate therewith, and a plurality of keys each of which has a movement in two directions and a movement of each of which in one direction will effect a movement of the denominational arresting-stop, whereas a movement in another direction will effect a movement of the column arresting-stop.

13. In a type-writing machine, the combination of a carriage, a denominational arresting-stop, denominational stops that coöperate therewith, a column arresting-stop, column-stops that coöperate therewith, a plurality of keys each of which has a movement in two directions and a movement of each of which in one direction will effect a movement of the denominational arresting-stop, whereas a movement in another direction will effect a

movement of the column arresting-stop, and means controlled by each of said keys for automatically releasing the carriage.

14. In a type-writing machine, the combination of a carriage, two independently-operable arresting-stops, each of which is movable to different distances, and a single key for moving said stops.

15. In a type-writing machine, the combination of a carriage, two independently-operable arresting-stops, a set of stops for each of said arresting-stops, and a single key that is movable in two directions, a movement in one direction effecting a movement of one arresting-stop, and a movement in another direction effecting a movement of the other arresting-stop.

16. In a type-writing machine, the combination of a carriage, two independently-operable arresting-stops, a set of stops for each of said arresting-stops, a single key that is movable in two directions, a movement in one direction effecting a movement of one arresting-stop and a movement in another direction effecting a movement of the other arresting-stop, and means for automatically releasing the carriage when said key is actuated.

17. In a type-writing machine, the combination of a carriage, two arresting-stops that are movable to different distances, a set of graduated stops for each of said arresting-stops, and a single set of keys that are movable in two directions, a movement in one direction effecting a movement of one arresting-stop and a movement in another direction effecting a movement of the other arresting-stop.

18. In a type-writing machine, the combination of a carriage, a denominational arresting-stop, an independently-operable column arresting-stop, said stops being movable to different distances and each stop having a set of coöoperating graduated stops, and a plurality of keys, each of which is movable in two directions and controls the movement to different distances of said arresting-stops.

19. In a type-writing machine, the combination of a carriage, a denominational arresting-stop, an independently-operable column arresting-stop, said stops being movable to different distances and each stop having a set of coöoperating graduated stops, a plurality of keys, each of which is movable in two directions and controls the movements to different distances of said arresting-stops, and means for automatically effecting a release of the carriage when any of said keys is actuated.

20. In a type-writing machine and tabulating mechanism, the combination of a carriage, a longitudinally-movable and pivoted key-lever, a stop which is actuated by the longitudinal movement of said key-lever, an independent stop which is actuated by the pivotal movement of the said key-lever, and stops which coöperate with said key-actuated stops.

21. In a type-writing machine and tabulating mechanism, the combination of a carriage, a longitudinally-movable and pivoted key-lever, a stop which is actuated by the longitudinal movement of said key-lever, an independent stop which is actuated by the pivotal movement of said key-lever, stops which coöperate with said key-actuated stops, and means controlled by either the longitudinal or pivotal movements of said key-lever for effecting the release of the carriage.

22. In a type-writing machine and tabulating mechanism, the combination of a carriage, a plurality of independently-operable longitudinally-movable pivoted key-levers, a stop that is moved to different extents by the longitudinal movements of each of said key-levers, an independent stop which is moved to different extents by the pivotal movements of each of said key-levers, and stops which coöperate with each of said key-actuated stops.

23. In a type-writing machine, the combination of a carriage, two arresting-stops, a set of graduated stops that coöperate with each arresting-stop, and key-actuated means for bringing either of said arresting-stops and its coöperating set of graduated stops into coöperative relation.

24. In a type-writing machine, the combination of a carriage, two arresting-stops, a set of graduated stops that coöperate with each arresting-stop, key-actuated means for bringing either of said arresting-stops and its coöperating set of graduated stops into coöperative relation, and means for automatically releasing the carriage when the key-actuated means are operated.

25. In a type-writing machine, the combination of a carriage, two independently-operable arresting-stops that are movable to different extents, a set of graduated stops that coöperate with each arresting-stop, and key-actuated means for bringing either of said arresting-stops into coöperative relation with its set of graduated stops.

26. In a type-writing machine, the combination of a carriage, two arresting-stops that are movable to different extents, a set of graduated stops that coöperate with each arresting-stop, key-actuated means for bringing either of said arresting-stops into coöperative relation with its set of graduated stops, and means for automatically releasing the carriage when the key-actuated means are operated.

27. In a type-writing machine, the combination of a carriage, two arresting-stops, a set of graduated stops that coöperate with each arresting-stop, and a single set of keys that are adapted to bring either of said arresting-stops and its coöperating set of graduated stops into coöperative relation.

28. In a type-writing machine, the combination of a carriage, two independently-operable arresting-stops that are each adapted to

be moved to different distances, a graduated stop that coöperates with each of said arresting-stops, and a single set of keys that are adapted to move either of said arresting-stops to different distances and to bring it into coöperative relation with its graduated stop.

29. In a type-writing machine, the combination of a carriage, two independently-operable arresting-stops that are each adapted to be moved to different distances, a graduated stop that coöperates with each of said arresting-stops, a single set of keys that are adapted to move either of said arresting-stops to different distances and to bring it into coöperative relation with its graduated stop, and means controlled by said keys for automatically releasing the carriage.

30. In a type-writing machine, the combination of a carriage, two independently-operable arresting-stops that are each adapted to be moved to different distances, a graduated stop that coöperates with each of said arresting-stops, and a single set of keys each of which is movable in two directions, the said keys being adapted to move either of said arresting-stops to different distances and to bring it into coöperative relation with its graduated stops, the arresting-stop moved depending on the direction of movement of the key and the distance to which said stop is moved depending on the key actuated.

31. In a type-writing machine, the combination of a carriage, two independently-operable arresting-stops that are each adapted to be moved to different distances, a graduated stop that coöperates with each of said arresting-stops, a single set of keys each of which is movable in two directions, the said keys being adapted to move either of said arresting-stops to different distances and to bring it into coöperative relation with its graduated stop, the arresting-stop moved depending on the direction of movement of the key and the distance to which said stop is moved depending on the key actuated, and carriage-releasing mechanism actuated by a movement of any key in either direction.

32. In a type-writing machine and tabulating mechanism, the combination of a carriage, key-actuated tabulating devices, and carriage-releasing means controlled by said keys and comprising a controlling-bar movable in two directions to effect a release of the carriage.

33. In a type-writing machine and tabulating mechanism, the combination of a carriage, key-actuated tabulating devices, and carriage-releasing means controlled by said keys and comprising a pivoted frame that is likewise adapted to receive a sliding movement and to effect a release of the carriage either by its pivotal or its sliding movement.

34. In a type-writing machine and tabulating mechanism, the combination of a carriage, tabulating devices therefor, keys for actuating

said tabulating devices and which are movable to different extents, and carriage-releasing means which comprise a controlling-bar against which the keys are adapted to bear 5 and that receives a uniform extent of movement from said keys.

35. In a type-writing machine and tabulating mechanism, the combination of a carriage, tabulating devices therefor, keys for actuating 10 said tabulating devices and which are movable in two directions, and carriage-releasing means which comprise a controlling-bar that receives a uniform extent of movement from 15 said keys during the movement thereof in either direction.

36. In a type-writing machine and tabulating mechanism, the combination of a carriage, tabulating devices, and a tabulating-key lever that controls the tabulating devices and which 20 is movable in two directions to control one or another of said tabulating devices depending on the direction of movement of said lever.

37. In a type-writing machine and tabulating mechanism, the combination of a carriage, 25 a series of tabulating-keys, each of which is mounted to receive an endwise movement and a pivotal movement, tabulating devices controlled by said keys, and carriage-releasing means comprising a frame that is moved at 30 each operation of a tabulating-key.

38. In a type-writing machine and tabulating mechanism, the combination of a carriage, a series of tabulating-keys, each of which is mounted to receive an endwise movement and 35 a pivotal movement, tabulating devices controlled by said keys, and carriage-releasing means comprising a pivoted frame that is likewise adapted to receive a reciprocating movement and to be moved in one direction or the 40 other at each operation of a tabulating-key, the direction of movement of the frame depending on the direction of movement of the keys.

39. In a type-writing machine and tabulating mechanism, the combination of a carriage, 45 tabulating devices, a tabulating-key lever that controls the tabulating devices and which is movable in two directions to control one or another of said tabulating devices depending 50 on the direction of movement of said levers, and carriage-releasing means controlled by the movement of said lever in either direction.

40. In a type-writing machine and tabulating mechanism, the combination of a carriage, 55 tabulating devices, a series of independently-operable pivoted tabulating-key levers, each of which is likewise adapted to slide and carriage-releasing mechanism which is controlled by said keys and comprises a pivoted and sliding 60 frame that is independent of the key-levers, the construction and relation of the parts being such that a sliding movement of a tabulating-key lever will effect a sliding movement of the frame to release the carriage, and a 65 pivotal movement of a tabulating-key lever

will effect a pivotal movement of the frame to release the carriage.

41. In a type-writing machine and tabulating mechanism, the combination of a carriage, tabulating devices comprising independently-actuatable stops, a series of independently-operable pivoted tabulating-key levers, each of which is likewise adapted to slide, and carriage-releasing mechanism which is controlled by said keys and comprises a pivoted and sliding frame that is independent of the key-levers, the construction and relation of the parts being such that a sliding movement of a tabulating-key lever will actuate one of said stops and will effect a sliding movement of the frame to release the carriage, and a pivotal movement of a tabulating-key lever will actuate another of said stops and will effect a pivotal movement of the frame to release the carriage. 75 80 85

42. In a type-writing machine and tabulating mechanism, the combination of a carriage, tabulating devices comprising independently-actuatable stops that are adapted to be moved to different extents by said tabulating-key levers, 90 a series of independently-operable pivoted tabulating-key levers, each of which is likewise adapted to slide, and carriage-releasing mechanism which is controlled by said keys and comprises a pivoted and sliding frame that is independent of the key-levers, the construction and relation of the parts being such that the sliding movements of the tabulating-key levers will move one of said stops different distances and will effect a sliding movement of the frame to 95 release the carriage, and the pivotal movements of tabulating-key levers will move another of said stops different distances and will effect a pivotal movement of the frame to release the carriage. 100 105

43. In a type-writing machine and tabulating mechanism, the combination of a carriage, tabulating devices, a key therefor which is movable in two directions, and means for preventing the key from moving in one direction when it starts to move in the other direction. 110

44. In a type-writing machine and tabulating mechanism, the combination of a carriage, tabulating devices, a key therefor which is adapted to receive a pivotal and a sliding movement, and means for preventing the key from moving in one direction when it starts to move in the other direction. 115

45. In a type-writing machine and tabulating mechanism, the combination of a carriage, tabulating devices, a key therefor which is adapted to receive a pivotal and a sliding movement, and means for preventing the key from sliding when it starts to receive its pivotal movement and to prevent it from receiving a pivotal movement when it starts to slide. 120 125

46. In a type-writing machine and tabulating mechanism, the combination of a carriage, tabulating devices, a pivoted key-lever therefor, which is likewise adapted to receive a 130

longitudinal movement, and guides in which said lever moves, the construction and arrangement being such, that when said lever starts to move in one direction it will be moved away from one guide and into the other and will be prevented from moving in any direction other than that permitted by the guide in which the lever is seated.

47. In a type-writing machine and tabulating mechanism, the combination of a carriage, tabulating devices, a pivoted key-lever therefore, which is likewise adapted to receive a horizontal movement, and a vertical and a horizontal guide in which said lever moves, the construction and arrangement being such that when said lever starts to move in the horizontal guide it will be moved away from the vertical guide and will be prevented from receiving a pivotal movement, and when the lever starts to move in the vertical guide it will be moved away from the horizontal guide and will be prevented from receiving a horizontal movement.

48. In a type-writing machine and tabulating mechanism, the combination of a carriage, tabulating devices, a pivoted key-lever therefore, which is likewise adapted to receive an endwise movement, and guides in which a free end of said lever is adapted to be seated and to move, the construction and arrangement of the parts being such that when the lever is moved in one direction the said free end thereof will be moved in one guide and away from the other and the lever will be prevented from moving in any direction except that permitted by the guide in which it is seated.

49. In a type-writing machine and tabulating mechanism, the combination of a carriage, tabulating devices, a pivoted key-lever therefore, which is likewise adapted to receive an endwise movement, and vertical and horizontal guides in which a free end of said lever is adapted to be seated and to move, the construction and arrangement of the parts being such that when the lever receives a pivotal movement the free end thereof will be moved in the vertical guide and away from the horizontal guide and the lever will be prevented from moving endwise or in a horizontal direction by a wall of the vertical guide, and when the lever starts to receive a horizontal or endwise movement it will be moved away from the vertical guide and will be prevented from receiving a pivotal movement by a wall of the horizontal guide.

50. In a type-writing machine and tabulating mechanism, the combination of a carriage, an arresting-stop, a plurality of sets of stops that are adapted to coöperate with said arresting-stop, means which afford a movement of said plurality of sets of stops, so as to bring one set to an operative position and to move another or other sets out of the operative position, and a plurality of keys controlling said arresting-stop and bringing it into coöpera-

tion with the different stops of said sets of co-operating stops.

51. In a type-writing machine and tabulating mechanism, the combination of a carriage, an arresting-stop, a plurality of sets of stops that are adapted to coöperate with said arresting-stop, means which afford a movement of said plurality of sets of stops, so as to bring one set to an operative position and to move another or other sets out of the operative position, and key-actuated means for moving the arresting-stop to different extents so as to coöperate with the different stops which have been moved to the operative position.

52. In a type-writing machine and tabulating mechanism, the combination of a carriage, an arresting-stop, a pivoted frame carrying a plurality of independent sets of stops, means for retaining the frame in the various positions to which it may be moved on its pivots, so as to bring and maintain one or another set of stops in the operative position and to move the other set or sets of stops out of the operative position, and a plurality of keys controlling said arresting-stop and bringing it into coöperation with different stops of said sets of coöperating stops.

53. In a type-writing machine and tabulating mechanism, the combination of a carriage, a plurality of stop-carrying bars carried thereby, means for moving said stop-bars and maintaining them in the position to which they are moved, so as to maintain the stops on one or more bars in the operative position and to maintain the stops on the other bar or bars in the inoperative position, and key-controlled tabulating devices that coöperate with said stops.

54. In a type-writing machine and tabulating mechanism, the combination of a carriage, three connected stop-carrying bars that are adapted to be moved relatively to the part which carries them so as to bring either one or two of said bars to the operative position, means for maintaining the bars in the position to which they are moved, and tabulating instrumentalities coöperating with the stops which are in the operative position.

55. In a type-writing and tabulating mechanism, the combination of a carriage; stops that are situated at a plurality of letter-space distances apart; stops that are situated at a single letter-space distance apart; means whereby said stops may be moved into or out of operative position; and tabulating devices that are adapted to coöperate with the stops that are in operative position.

56. In a type-writing and tabulating mechanism, the combination of a carriage; stops that are situated at a plurality of letter-space distances apart; stops that are situated at a single letter-space distance apart; said stops being pivotally connected to the carriage so that they may be moved into or out of operative position and be maintained in such posi-

tion; and tabulating devices that are adapted to coöperate with the stops that are in operative position.

57. In a type-writing machine and tabulating mechanism, the combination of a carriage, three sets of stops, the stops of two sets being situated at a letter-space distance apart, whereas the stops of the third set are situated a plurality of letter-space distances apart, means 10 for maintaining one or two of said sets of stops in the operative position as may be desired, and tabulating devices that are adapted to coöperate with the stops which are in the operative position.

15 58. In a type-writing machine and tabulating mechanism, the combination of a carriage, a set of graduated stops that are situated a plurality of letter-space distances apart, a second set of graduated stops situated a letter-space distance apart, and means coöoperating with either set of stops to arrest the carriage.

20 59. In a type-writing machine and tabulating mechanism, the combination of a carriage, a set of graduated stops that are situated a plurality of letter-space distances apart, a set 25 of graduated stops situated a letter-space distance apart, and an independently-actuatable stop coöoperating with each set of graduated stops.

60. In a type-writing machine and tabulating mechanism, the combination of a carriage, 30 a set of graduated stops that are situated a plurality of letter-space distances apart, a set of graduated stops situated a letter-space distance apart, an independently-actuatable stop 35 coöoperating with each set of graduated stops, and means for automatically releasing the carriage on the operation of either of said independently-actuatable stops.

61. In a type-writing machine and tabulating mechanism, the combination of a carriage, a set of graduated stops that are situated a plurality of letter-space distances apart, a set 40 of graduated stops situated a letter-space distance apart, an independently-actuatable key- 45 operated stop for each set of graduated stops, the same key being capable of actuating either independently-actuatable stop, and means for automatically releasing the carriage on the operation of either of said independent stops. 50

Signed at the borough of Manhattan, city of New York, in the county of New York and State of New York, this 13th day of April, A. D. 1903.

JAMES OPPENHEIM.
